METHOD AND APPARATUS FOR REMOVING
WATER FROM CLOTHES

Arnold Erlanger, New York, N. Y., assignor, by
mesne assignments, to American Machine and
Metals, Inc., New York, N. Y., a corporation of
Delaware

Application March 3, 1931, Serial No. 519,790

8 Claims. (Cl. 210—76)

This invention relates to laundry methods and apparatus for removing water from clothes.

An object thereof is to formulate a simple and practical method for wringing clothes.

5 Another object is to formulate a simple and efficient method for wringing and removing clothes from centrifugal laundry extractors.

Another object is to provide means for facilitating handling of the "wash" during certain 10 stages of its passage through the laundry.

A further object is to provide a simple and efficient container for holding the "wash" during the extracting operation, which container may be removed bodily from the extractor at the end of 15 that operation, without disabling the extractor by the removal of any essential part thereof.

A further object is to provide a simple, practical and inexpensive removable container for laundry extractors, from which the "wash" may 20 be easily and quickly released and dumped by gravity at the place where the next operation affecting the "wash" is to occur.

Other objects will be in part obvious and in part pointed out hereinafter.

25 The invention accordingly consists in the features of construction, combination of elements, arrangements of parts and in the several steps and relation and order of the same, all as will be herein illustratively described and the scope of 30 the application of which will be indicated in the following claims.

In the accompanying drawings in which is shown certain of the various possible embodiments of my invention:

35 Fig. 1 is a partial vertical section taken through the axis about which the extractor basket rotates, showing a preferred form of inner container and illustrating in broken lines the manner of its removal;

40 Fig. 2 is a sectional view of the inner container after its removal from the extractor, at a stage in its handling when the "wash" is about to be dumped upon a shake-out table;

45 Fig. 3 is a view illustrating the completion of the dumping operation;

Fig. 4 is a top plan view of a modified form of inner container shown in operative relation to the extractor basket;

50 Fig. 5 is a sectional view of the container of Fig. 4 shown in course of removal from the extractor basket; and

Fig. 6 is a side elevation of the container of Fig. 5 after the "wash" has been dumped.

55 Similar reference characters refer to similar

parts throughout the various views of the drawings.

Passage through a laundry of clothing or other articles constituting the "wash" usually involves the accomplishment of several successive correlated operations. 5

After the reception, sorting, etc., the "wash" is delivered to a cylinder washing machine which receives it distributed in a plurality of different compartments, where it is washed in the presence 10 of water containing soap or other detergent agents. At the end of the washing operation the contents of one or more of these compartments is customarily discharged into a truck, which is rolled along the floor of the laundry to a centrifugal extractor, where approximately 50% of 15 the water is removed, after which it is taken from the extractor and transferred to a shake-out tumbler or, alternatively, to a shake-out table. Here the tightly packed and interlayered mass of 20 moist clothes is shaken out and prepared for ironing by means of ironing machines suitable for the different kinds of articles included in the "wash".

Upon arrival at the extractor for the purpose 25 of wringing, the "wash" is usually removed from the truck by hand and carefully placed in the basket of the extractor in such a way as evenly to distribute the load, so as to avoid an unbalanced condition of the basket during its period 30 of rotation. The basket is then rotated at high speed until a sufficient quantity of moisture has been removed, after which the machine is stopped and the clothes are removed by hand. This last is a time-taking and tedious operation, for during 35 extraction the clothes have become very tightly intermixed and pressed together.

In an effort to facilitate the removal of the clothes from the extractor, resort has been had, in the past, to making the regular basket of the extractor detachable from its driving mechanism through the removal of a nut or the manipulation of other mechanical locking devices, and in some instances specially constructed extractor baskets, removable from the extractor for unloading, have been used; but whether the baskets were of the regular standard type or of special construction, they needed, in either case, to be rigidly connected with the extractor spindle, and some readily releasable locking means had to be provided to render the basket quickly detachable. By providing a removable basket, it was possible to lift the basket bodily from the machine at the end of the wringing operation and to carry it away 50 to the station where its contents were to be re- 55

removed. Provision then had to be made for lifting the removed basket and turning it upside down so that the clothes might fall out. As the weight of the average load of a laundry basket, after 5 extraction of the removable moisture, is approximately 450 lbs., exclusive of the weight of the heavy metal basket itself, it will be realized that such removal and up-ending is not easily accomplished and that as a result the advantages gained 10 in the use of such constructions are in a great measure offset by the many disadvantages concurrent therewith. Beside the difficulty found in handling such baskets, a further disadvantage results from their use, by reason of the fact that 15 they constitute an essential part of the extractor itself, so that after the removal of a basket from a machine, the latter becomes useless until such time as the basket has been returned to and re-installed therein.

20 In order to rid the operation of unloading of the disadvantages attendant upon the use of detachable metal baskets, the present invention provides a fabric, or rubberized fabric, or other suitable inner container which is formed upon a mandrel, or in any other appropriate manner, so that the sides and bottom thereof conform naturally to the side walls and bottom of the basket of the extractor with which it is intended for use. The container is made flexible enough, however, so 25 that after its removal from the extractor, and while in a state of suspension or after it has been lowered upon the shake-out table, certain parts thereof may be released from the suspension means, when, in one form thereof, the container 30 will turn inside out to permit the "wash" to fall by gravity upon the shake-out table, or, if desired, into the mouth of a shake-out tumbler. In another form of the device the bottom may drop down and open out to accomplish the same de- 35 sired end.

The side walls of the container are preferably made of open-mesh woven material, but may be constructed of a close-mesh rubber covered material in which a great number of thimbled or 40 eyeletted perforations have been made. These 45 perforate side walls lying against the side walls of the extractor basket, which are of the usual perforate construction, permit the centrifugal removal of the water contained in the "wash", as 50 freely as if the clothes were placed directly within the extractor basket.

Referring to the drawings,

The extractor of the present invention is best 55 shown in Fig. 1 and comprises a stationary frame 10, supporting a stationary outer casing or curb 11, which substantially encloses the movable extracting mechanism. A journal member or bearing unit 12 serves rotatably to support the extractor spindle 13 and is mounted upon a supporting spider 14, which is suspended from the frame 10 by means of suspension rods 15. These rods are provided, top and bottom, with flexible or resilient washers 16 adapted to permit the spider 14 and the extracting mechanism mounted thereon 60 to oscillate independently of the supporting casing 11, thus in a measure providing compensation for unbalanced basket loads.

Any suitable driving element, such as an electric motor 17, is provided to rotate the spider 14. 70 An extractor basket 25 is rigidly mounted upon the spindle 13 and comprises a casting 18 forming the bottom of the basket, a casting 19 forming the upper lip or edge of the basket, and a perforated side wall 20 of cylindrical conformation, 75 the latter being supported by reinforcing bands

21. The basket is coupled to the spindle for rotation therewith by means of any suitable key 22 and is held in its properly seated position upon the tapered spindle by means of a flanged nut 23 threaded upon the end of said spindle.

The usual method of operation of an extractor of this type when it is used as a laundry wringer, is as follows: The wet clothes from the washing machine are placed in the basket, the motor is started and the spindle and basket set in rapid motion. The centrifugal action causes the load to move over against the perforated wall of the basket and assume somewhat the position indicated by broken line 49 in Fig. 1; and the water to be thrown outwardly from the clothes through 15 the perforations and delivered to the interior of the curb 11, from which it may be drained in any suitable manner. When the operation is finished the motor is stopped and the basket brought to 20 a standstill, when the clothes may be removed by hand.

This method of operation is radically changed in carrying out my invention, by first placing within the extractor basket an inner container, indicated generally by the numeral 25. As stated 25 in the foregoing general discussion, this container is of semi-flexible construction, and is molded or formed to provide a normally upright cylindrical wall 26 and an inwardly and upwardly extending bottom portion 27, shaped to conform respectively 30 to the side wall, bottom and hub of the basket. At its upper edge the container wall 26 is turned over to provide a lip 28 adapted to fit over the edge of the basket rim member 19, and this lip is provided with a plurality of spaced eyes or 35 grommets 29 for engagement with a suitable suspension means, whereby the removal of the basket may be easily accomplished. A circular opening 30 is provided at the center of the annular bottom portion 27, adapted to fit over the 40 hub of the basket, and the edge of the material about this circular opening is provided with a plurality of grommets 31 securely attached thereto, also for the purpose of permitting attachment 45 of a suspension means.

The side wall 26, as mentioned above, is open-meshed or perforated to make it readily pervious to water and, along the line where the wall 26 joins the bottom portion 27, the material is distorted or given a permanent set, as indicated at 50 32.

In loading and unloading the extractor, according to my invention, the container 25 is placed in the extractor basket so as nicely to fit the interior of the sides and bottom thereof, the lip 55 29 being caught over the edge 19 of the basket. The wet clothing or other articles are carefully placed within the container, the extractor cover (not shown) is closed and the basket set in motion. Water is now driven out through the perforated sides of both container and basket until the "wash" becomes sufficiently dry, when the basket is brought to rest and the cover is thrown back out of the way. For removing the container from the extractor basket a special sling may be 60 provided, comprising a ring member 33 to which is attached a plurality of relatively long ropes or chains 34 and a plurality of short ropes or chains 35. Each sling member 35 is provided at its free end with a hook 36 adapted to engage the eye of one of the grommets 29, and the lower end of each of the suspension members 34 is made fast to the eye of one of the grommets 31, or, if preferred, the members 34 may be provided with hooks at their lower ends similar to hooks 36. 75

The sling supported by its ring 33 from a hook 38 carried by a suitable trolley hoist (not shown), is brought over and down to the container 25 and its hooks made fast thereto in the proper manner, or, alternatively, the sling may be left in the container during the extracting operation and attached to the hoist hook 38 when it is desired to remove it.

The hoist is now operated to lift the container 10 with its load of clothes bodily from the extractor basket and to transport it to the shake-out table, indicated in Figs. 2 and 3 by the numeral 39. As tension is put upon the suspension cords 35, the outer walls of the container are drawn in some- 15 what, as shown by broken lines in Fig. 1, which provides clearance enough for the ready removal of the container from the basket. At the shake-out table the hooks 36 are released from the eyes 29 and the outer edge 28 of the side wall is drawn down by the weight of the load until the container 20 assumes somewhat the condition shown in Fig. 3, when the load is deposited upon the top of the shake-out table. As mentioned above, the container may be allowed to rest lightly on the shake-out table so as to provide slack enough to facilitate the unhooking of the sling members 35 from the eyes 29, but it is perfectly practicable to furnish trip hooks for engagement with these eyes so that they may be released even while under 25 tension.

When empty, the flexible container may be set down out of the way or be returned to the extractor, but in any case, it should be understood, the extractor need not remain idle for more than 30 a brief interval of time. As soon as one container has been removed from the extractor another may be substituted, and the machine again put in operation. Such a method of operation would not be practicable with constructions made as heretofore, where the regular basket of the extractor was made removable, for the expense of maintaining extra baskets for each extractor would be prohibitive. In the case of such constructions the machine is, in the absence of the basket put entirely out of commission, since the basket is an essential part thereof. With the device of the present invention, however, even were there no extra container handy, the machine could be operated in the usual way, with the extractor basket holding the clothes.

In Figs. 4, 5 and 6 is illustrated a modified form of inner container, comprising a pervious body portion 126, having an upper edge 128, supplied with suspension eyes 129. These eyes are attached 35 to suspension cords 135, which may be made removable with respect either to the container itself or the hoist hook 138. The bottom portion of the container or bag, as it may be called, comprises a plurality of overlapping flaps 127, each of which 40 is provided with a ring 131 through which a pair of draw-cords 134 and 134' are reeved. These draw-cords, when thrown over the hook portion of the trip-hook 138, and when the container is suspended from the hook, draw the flaps 127 up- 45 wardly and inwardly to close the bottom of the container, as is indicated in Fig. 5. In this position it is placed within the extractor basket.

During extraction the draw-cords 134 and 134' will lie on the bottom of the container beneath 50 the clothes. When moved in its suspended condition to the shake-out table, the trip portion of hook 138 may be released from the draw-cords by jerking the operating cord 138'. This will release the draw-cords and permit the flaps to descend beneath the weight of the load, dumping 55

the load upon the shake-out table, as indicated in Fig. 6.

While it is not necessary in either form of the invention to mold the container to the shape of the extractor basket, it has been found preferable 5 to do so, for it facilitates placing the container properly within the basket and also makes it more easily handled and operated. It should be noted that applicant does not confine himself or wish to be limited to any particular manner of suspending the container in its closed condition, or to any specific means for releasing the suspension cords when it is desired to dump the load.

From the foregoing it will be seen that applicant has formulated a process well adapted to 10 attain the objects set forth above and has provided a simple and inexpensive removable baglike container adapted to hold the "wash" during the wringing operation, without hindering the efficiency of extraction, which container may be 15 readily emptied without the aid of complicated machinery for turning it upside down.

As many possible embodiments may be made of the above invention without departing from the scope thereof, it is to be understood that all 20 matter herein set forth or shown in the accompanying drawings is to be interpreted as illustrative and not in a limiting sense.

I claim as my invention:

1. In apparatus of the character described, in 30 combination, an extractor for wringing clothes comprising a perforate basket, and a removable container serving to line the basket and hold the clothes during the operation of the extractor and adapted to be lifted with its contents bodily 35 from the extractor basket, said container being formed of a perforate rubberized fabric material.

2. A centrifugal laundry-drying machine including in combination a perforate centrifugal basket rotatably mounted within a casing, a flexible bag-like container shaped to fit within the basket and means for removing the container and its contents from the basket comprising a semi-flexible, flanged supporting ring that can be turned inside out at the top of the container 45 shaped to gravitally support the upper rim of the container upon the rim of the basket and means for lifting said ring from the basket rim to remove the container and its contents from the basket.

3. A centrifugal laundry-drying machine including in combination a perforate centrifugal basket rotatably mounted within a casing, a flexible bag-like container having a semi-flexible top ring by which it is attached to the basket shaped 55 to fit within the basket, means for lifting the container and its contents from the basket, and means for turning the bag and the top ring inside-out to empty the contents thereof.

4. A centrifugal laundry-drying machine including in combination a perforate centrifugal basket rotatably mounted within a casing, a flexible bag-like container having a semi-flexible top ring by which it is attached to the basket shaped to fit within the basket, means for lifting the container and its contents from the basket, and means for turning the bag and the top ring inside-out to empty the contents thereof comprising supporting devices connected to the upper 60 rim of the container and additional supporting devices connected to the bottom of the container and means for releasing the rim support while continuing to support the bottom, and thereby 65 causing the upper part of the container to col- 70 75

lapse and reverse the container and the top ring.

5. In a laundry centrifugal extractor, in combination, an underdriven basket, a pervious lining for the basket, a top ring of flexible material
5 removably fitted around the upper edge of the basket and attached to the lining, hoisting means, connecting elements from the hoisting means to the basket top ring for lifting the top ring vertically and axially; other connecting ele-
10 ments to the central portion of the lining and the basket load; means for releasing one set of connecting elements to drop the basket load.

6. In a laundry centrifugal extractor, in combination, an underdriven basket, a pervious lining for the basket having a top ring resting upon and supported by the top edge of the basket, said top ring being formed of semi-flexible, resil-
15 ient material capable of turning inside out.

7. A centrifugal laundry drying machine including in combination a perforate centrifugal basket, having a rigid top rim on the upper edge of the basket, rotatably mounted within a cas-
5 ing, a flexible bag-like container to fit within the basket, a flanged, semi-flexible annular lip attached to the bag and adapted to be fitted over said rim for supporting the bag.

8. For use in a centrifugal laundry drying ma-
chine, a flexible bag-like container to fit within
10 a centrifugal basket, said container having side
walls of perforate, resilient material, an annular
semi-flexible lip at the top edge of the side walls
and formed integrally therewith by which the 15
container may be supported.

ARNOLD ERLANGER.
